UNITED STATES PATENT OFFICE.

JOSEPH F. ROTHE, OF GREEN BAY, WISCONSIN.

CATCH-BASIN.

1,117,250.

Specification of Letters Patent. Patented Nov. 17, 1914.

Application filed June 17, 1912. Serial No. 703,998.

To all whom it may concern:

Be it known that I, JOSEPH F. ROTHE, a citizen of the United States, residing at Green Bay, county of Brown, and State of Wisconsin, have invented new and useful Improvements in Catch-Basins, of which the following is a specification.

My invention relates to improvements in catch basins.

10 The object of my invention is to provide a form of metallic catch basin, composed of separable sections, which may be easily assembled, cleaned and repaired, the parts being readily separable by a person who understands the requirements for such separation.

15 It is well understood that catch basins should be water tight, or substantially so, and it is therefore essential that the several 20 sections should be so formed that when assembled they can be rendered water tight without loss of time and at comparatively little expense.

25 My invention has in view the provision of water tight joints for the sections, regard being had for simplicity, durability, and convenience in manipulation.

30 In the drawings—Figure 1 is a vertical sectional view of my improved catch basin. Fig. 2 is a fragmentary exterior view of the trap supporting section and a superposed section. Fig. 3 is a sectional view, drawn on line $x-x$ of Fig. 1. Fig. 4 is a plan view of the catch basin cover. Fig. 5 is a sectional view of the same, drawn on line $y-y$ of Fig. 4.

35 Like parts are identified by the same reference characters throughout the several views.

40 The lower section A of my improved catch basin cistern comprises a cup shaped member, provided at its upper margin with an interior shoulder a and an exterior outwardly projecting flange a' . A cylindrical section C is mounted with its lower margin resting upon the margin a within the flange a' , the upper margin of this section being provided with a shoulder a^2 and an outwardly extending flange a^3 , similar respectively to the shoulder a and flange a' on the section A. This section C receives another cylindrical section C', which at its upper end is provided with a shoulder a^4 and an outwardly projecting flange a^5 . The annular flanges a' , a^3 and a^5 project outwardly and away from the side wall of the section

above, and form an annular pocket b , V-shape in cross section, for the reception of cement, whereby the joints between the sections are made liquid tight. The V-shape 60 form of the pockets facilitates tamping the cement in position to effectively seal the joint.

An elbowed member D is provided, near one end, with an external flange d , and this end of the member D is adapted to fit an aperture in the side wall of the member C. The other leg of the member D extends downwardly within the member C (or member A). The member D is also provided with ears d' , and the wall of the member C is provided with corresponding notches d^2 , through which the ears d' may pass when in registry with such notches, said ears d' being, however, adapted to engage the outer 70 surface of the member C when the member D is partially rotated after the ears d' have passed through said notches d^2 . The notches d^2 are so located that when the ears d' are in registry therewith, the downwardly extending leg of the member D will not occupy a vertical position. Therefore, after the ears have been passed through the notches from the interior of the catch basin cistern to the exterior thereof, the member 80 85 D will be locked in position, when the downwardly extending leg is swung to a vertical position. Said member D, therefore, tends to swing by gravity to a locking position after the flange leg thereof has been passed 90 through the aperture in member C. It will of course be understood that the sewer or drain pipe will be connected to the projecting end of the member D in any suitable manner.

95 A catch basin cap F is mounted upon the upper section of the catch basin cistern. It is preferably provided with a downwardly projecting flange F' , adapted to rest upon the shoulder a^4 and it is also provided with 100 an outwardly projecting flange F^2 , adapted to rest upon the upper margin of the flange a^5 . The cap F is provided with the usual aperture, which may be closed by a lid G, said lid being secured in position by 105 lips g , which pass under the margin of the opening in the cap and by a latch g' , pivotally connected to the lid. The pivot pin I, which connects the latch g' to the lid, is provided with a triangular head J, at its 110 upper end, said head being received in a socket K in the lid substantially as shown

2
in Fig. 5. The cap F has its under surface beveled at the point where the latch g' engages it, whereby, as the latch moves along this beveled surface, the lid is bound firmly in position. It will of course be understood that when the latch is swung out of engagement with the surface H, the lid will be released for removal. The triangular head J will, however, prevent the removal of the lid by means of an ordinary wrench, a special tool being required for adjusting the latch.

I claim:—

1. A catch basin having an aperture in one of the side walls, and having notches in the margins of said aperture, in combination with an elbowed trap member having one leg adapted to project through said aperture, in position for connection with a sewer drain pipe, and provided with a flange adapted to engage the interior surfaces of the marginal walls of said aperture and to cover said notches, said member being also provided with outwardly projecting ears adjacent to said flange, adapted to pass through said notches and to engage by rotation upon the exterior wall of the cistern, when the inner leg of the elbow is in a substantially vertical downwardly extending position.

2. A catch basin having an aperture in 30 one of the side walls, and having notches in the margins of said aperture, in combination with an elbowed trap member having one 35 leg adapted to fit said aperture and provided with a flange adapted to engage the interior surfaces of the marginal walls of said aperture and to cover said notches, said member being also provided with outwardly projecting 40 ears adjacent to said flange, adapted to pass through said notches and to engage by rotation upon the exterior wall of the cistern, said notches being so located that the 45 lips will pass through them when the other leg of the elbowed member is in a downwardly inclined position and engage the exterior wall when such other leg of said member is in a substantially vertical downwardly extending position within the cistern, whereby said elbowed member may drop by gravity to a locking position, substantially as described.

In testimony whereof I affix my signature in the presence of two witnesses.

JOSEPH F. ROTHE.
